(57) **CLAIM**

We claim the ornamental design for front portions of a D-handle component of a latch assembly, as shown and described.

DESCRIPTION

FIG. 1 is a perspective view of front portions of a D handle component of a latch assembly showing front, left and first end features of our new design;

FIG. 2 is a front view thereof, it being seen and understood that left and right "halves" of the handle present appearances that are identical except that each is a mirror image reversal of the other;

FIG. 3 is a perspective view showing front, right and first end features thereof;

FIG. 4 is a perspective view showing front and first end features thereof; and,

FIG. 5 is a perspective view showing front, left and opposite end features thereof.

The broken line disclosure in the drawings is provided for illustrative purposes only and forms no part of the claimed design.
